UNITED STATES PATENT OFFICE.

STEPHEN KRONBURGER, OF HOBOKEN, NEW JERSEY, ASSIGNOR TO MELITA WHITE METAL CASTING CO., OF NEW YORK, N. Y., A COPARTNERSHIP CONSISTING OF JOHN EXPOSITE, JOSEPH MIFSUD, PAUL MIFSUD, AND LORENZO MICALLEF.

DESIGN FOR A COMBINED LAMP STAND AND CLOCK.

Application filed April 7, 1923. Serial No. 5,713. Term of patent 3½ years.

To all whom it may concern:

Be it known that I, STEPHEN KRONBURGER, a citizen of the German Republic, and a resident of Hoboken, in the county of Hudson and State of New Jersey, have invented and produced a certain new, original, and ornamental Design for a Combined Lamp Stand and Clock of which the following is a specification, reference being had to the ac-

companying drawings, forming part hereof, in which—

Fig. 1 is a front elevation of my new design, and

Fig. 2 is a side view thereof.

I claim:

The ornamental design for a combined lamp stand and clock as shown.

STEPHEN KRONBURGER.
